United States Patent [19]

Barrett

[11] Patent Number: Des. 340,696

[45] Date of Patent: ** Oct. 26, 1993

[54] BALL-OPERATED CONTROL DEVICE FOR ELECTRONIC CIRCUITS

[75] Inventor: John B. Barrett, Paso Robles, Calif.

[73] Assignee: Appoint, Paso Robles, Calif.

[**] Term: 14 Years

[21] Appl. No.: 792,059

[22] Filed: Nov. 13, 1991

[52] U.S. Cl. D13/158; D14/107

CLAIM

The ornamental design for a ball-operated control device for electronic circuits, as shown and described.

DESCRIPTION

FIG. 1 is a perspective view of a ball-operated control device for electronic circuits showing my new design;

FIG. 2 is a top plan view of the device;

FIG. 3 is a bottom plan view of the device;

FIG. 4 is a side elevational view of the device;

FIG. 5 is a front elevational view of the device; and,

FIG. 6 is a rear elevational view of the device.
